UNITED STATES PATENT OFFICE.

TRUEL T. LEE, OF AMOS, ARKANSAS.

SPRING-CLIP.

1,271,043.

Specification of Letters Patent.

Patented July 2, 1918.

Application filed December 22, 1917. Serial No. 208,360.

To all whom it may concern:

Be it known that I, TRUEL T. LEE, a citizen of the United States, residing at Amos, in the county of Baxter and State of 5 Arkansas, have invented certain new and useful Improvements in Spring-Clips, of which the following is a specification, reference being had to the accompanying drawings.

10 This invention relates to an improved spring clip and has for its primary object to provide a simply constructed and very serviceable clip or fastener of that character which is used for holding together a plurality of paper sheets, cards, or analogous articles.

It is one of the important objects of the invention to provide a clip or fastener constructed from a single length of resilient 20 wire bent upon itself to afford a multiplicity of gripping points so that the paper sheets or other articles will be securely held.

More specifically, it is the object and purpose of my invention to provide a fastening 25 clip of the above character which is particularly serviceable in holding together adjacent cards when arranged in rows or columns, the edges of the cards being insertable into opposite ends of the clip between the 30 gripping portions thereof.

And it is likewise a general object of my invention to provide a clip or fastening device having the above noted advantageous 35 features which is at the same time exceedingly simple in its construction and can be produced in large quantities at comparatively small cost.

With the above and other objects in view the invention consists in the improved clip 40 construction which will be hereinafter more specifically claimed and illustrated in the accompanying drawings in which similar reference characters designate corresponding parts throughout the several views and 45 wherein:

Figure 1 is an elevation showing the use of my improved clip in holding cards or like articles together when arranged end to end;

Fig. 2 is a sectional view taken on the line 50 2—2 of Fig. 1;

Fig. 3 is a view similar to Fig. 1 illustrating the device used in the manner of the ordinary paper clip; and

Fig. 4 is an edge view.

55 Referring in detail to the drawing 5 designates generally the single length of resilient

wire of requisite gage or thickness from which the clip is formed. This length of wire is bent upon itself to provide a straight intermediate portion 6 of predetermined length. From the ends of this straight portion 6 of the wire, said wire is bent to provide the portions 7 extending upon one side of the portion 6 and in convergent relation to each other. The portions 6 and 7 are integrally connected by the curved or rounded portions 8.

In advance of the point at which the portion 7 of the wire would intersect if extended, the wire is again bent at an obtuse angle 70 with respect to the portion 7 to provide the oppositely extending longitudinal side portions 9 which are disposed in substantially parallel relation to the straight side portions 6 of the clip. These portions 9 at their inner 75 ends are in overlapping relation and are normally held in close contact upon each other by the inherent resiliency of the metal, thereby affording a gripping point as indicated at 10.

At the outer ends of the portions 9 of the wire, the ends of the wire are bent and extended inwardly, as at 11 in intersecting relation to the wire portions 7. These points of intersection of the wires 7 and 11 afford additional gripping points 12 at the 80 opposite ends of the clip. The portions 11 of the wire terminate in spaced relation to the straight side portions 6 of the clip and the terminal portions are angularly 85 bent, as at 13, and disposed in intersecting relation to each other, said terminal portions extending toward the side portion 9 of the clip. By thus disposing the wire terminals in intersecting relation, a gripping 90 point 14 is afforded at the approximate center of the clip which is in alignment with the gripping points 12. Thus there is provided four separate and distinct points 95 at which the wire clip will have a gripping 100 action upon the articles.

In the use of my improved clip for the purpose of securing together a series of post cards or similar articles arranged in columns or rows, the edge of one card is engaged between the intersecting portions 7 and 11 of the wire at one end of the clip and moved to the approximate center of the clip where the marginal edge of the card will be engaged also by the gripping portions 10 and 14 of the clip. The second card is then inserted into the opposite end 105 110

2
of the clip between the intersecting wire portions 7 and 11 in a like manner. It will be manifest that the overlapping gripping portions 10 at one side of the wire clip upon the meeting marginal edges of the cards will effectively hold the cards against oscillation while the additional spaced gripping points 12 and 14 of the clip along the central longitudinal line thereof afford additional means of security and prevent the casual shifting movement of the clip or the cards with respect to each other.

The clip may of course also be employed in the usual manner for holding together sheets of paper or other documents, as shown in Fig. 4 of the drawing, and when so used, the resiliently yieldable portions of the clip disposed upon opposite sides of the paper sheets operate to afford a maximum gripping action at a plurality of spaced points on each side of the sheets, which will effectively obviate the possible loss of the individual sheets. The rounded corners 8 of the clip afford ample space for the marginal edges of the paper sheets and minimize the danger of tearing or mutilating the marginal edge of the paper sheets in the application of the clip.

It will be apparent that my improved clip can be very easily and quickly applied to the paper sheets or other articles. The clip produced in the manner above described is substantially of rectangular elongated form, and is not liable to be easily bent or distorted, as the several parts when in their normal condition render the clip as a whole, relatively rigid.

From the foregoing description taken in connection with the accompanying drawing, the construction and manner of use of my improved clip or fastener will be clearly and fully understood. The device can of course be made in various sizes, the gage or thickness of the wire being correspondingly increased or decreased. I have above referred to what I have found to be the preferred form and construction of the device in practical use, but it will be apparent that the clip is susceptible of certain modifications in the form and proportion of its various parts. Accordingly, I reserve the

privilege of resorting to all such legitimate changes as may be fairly embodied within the spirit and scope of the invention as claimed.

55

Having thus fully described my invention, what I claim and desire to secure by Letters Patent is:—

1. A clip formed from a single length of resilient wire having intersecting gripping portions at each end of the clip and other intersecting gripping portions at the approximate center of the clip, and additional gripping portions laterally spaced from the last named intersecting portions of the clip, all of said gripping portions operatively engaging an article held by the clip.

60

2. A clip formed from a single length of resilient material having a straight side portion 6, and additional side portions 9 in resilient contact with each other to afford a gripping point, the end portions of the material forming an angle with respect to said side portions 9 and said end portions having resilient engagement upon each other intermediate of the side portion 6 and the side portions 9 to provide an additional gripping point, said end portions of the material terminating contiguous to the resiliently engaged side portions 9.

70

3. A clip comprising a single length of resilient wire consisting of a straight side portion 6, inclined portions 7 and additional side portions 9 extending longitudinally in relatively opposite directions and lapped upon each other at their inner ends to afford gripping portions, the said wire being extended inwardly from said side portions 6 and 9 to provide intersecting portions 7, 11, at opposite ends of the clip affording additional gripping portions, the terminals of the wire forming an angle with said intersecting portions and also disposed in intersecting relation to afford additional gripping portions 13 at the approximate center of the clip.

80

In testimony whereof I hereunto affix my signature in the presence of two witnesses.

TRUEL T. LEE.
